ABSTRACT OF THE DISCLOSURE

This invention relates generally to a cathode ray tube of the type having a single gun and a post acceleration and focusing tube, and more particularly to such a cathode ray tube which has provided therewith an improved color switching device which includes two pairs of electrodes which are provided on opposite sides of the outer surfaces of the neck portion of the cathode ray tube, and two pairs of inner electrodes which are made of a low resistance material and which are located in positions corresponding to the outer electrodes. A layer of high resistance material is provided around the inner electrodes. The color switching is accomplished by applying switching signals in opposite directions to the two pairs of outer electrodes.

Background of the invention

This invention is particularly directed to improvements in color picture tubes of the type in which an electron beam is deflected through the use of two electrostatic fields, the purpose of the deflection being to alter the incidence angle of the electron beam to the grid in order to accomplish color switching. It is well known by those skilled in this art that color switching is effected by deflecting an electron beam with a magnetic field in order to change the incidence angle of the electron beam to the grid. It is also well known that an electron beam is electrostatically deflected in a monochrome tube. When a magnetic field is utilized for such a purpose, however, it requires the utilization of large power and results in extensive unwanted radiation. In addition, this method of deflection can be employed for a line sequential color television system but cannot be employed for a dot sequential system. In view of this fact those skilled in the art have considered that color switching can be effected by conventional electrostatic deflection rather than by the use of a magnetic field. The utilization of conventional electrostatic deflection, however, also results in various problems such as the provision of the power source for the electrostatic field generating electrodes and in providing shielding for the neck of the tube since the neck must be longer than in conventional cathode ray tubes. These disadvantages of the prior art, however, are overcome by the present invention by providing inner and outer electrodes respectively on the inside and outside of the neck portions of the cathode ray tube. These inner and outer electrodes are electrostatically coupled and the outer electrodes are adapted to be grounded in DC current in order to eliminate the problems encountered in the prior art.

Summary of the invention

In view of the foregoing the primary object of the present invention is to provide a one-gun color picture tube in which electrodes are provided on the outer and inner surfaces of the neck portion of the cathode ray tube and in which the electron beam is deflected through the

2

utilization of low power in order to provide color switching.

Another object of the present invention is to provide a one-gun color picture tube with a simplified one-gun color demodulator circuit.

Still another object of the present invention is to provide a one-gun color picture tube which minimizes color distortion and unnecessary radiation and which is thereby stable in operation.

These and further objects, features and advantages of the present invention will appear from the following detailed description of a preferred embodiment of the invention which is to be read in conjunction with the accompanying drawings in which like components of the several views are identified by the same reference numeral.

Brief description of the drawings

FIG. 1 is a schematic diagram in block form illustrating one example of a cathode ray tube of the present invention as applied to a color television picture tube;

FIG. 2 is an enlarged view of a portion of FIG. 1 and illustrating the principal parts of the present invention;

FIG. 3 is a cross section taken on the line 3—3 of FIG. 2;

FIG. 4 is an electrical equivalent circuit diagram of the principal components illustrated in FIG. 2; and

FIG. 5 is a wave form representative of a color switching signal.

Description of the preferred embodiment

Referring now to the drawings and particularly to FIG. 1, the reference numeral 11 indicates an antenna and the reference numeral 12 indicates a color signal transmission system from which are obtained a luminance signal Y, a chrominance signal C_S which is demodulated from a subcarrier, and horizontal and vertical synchronizing pulses which are identified respectively as P_H and P_V. The color cathode ray tube is identified by the numeral 13. The cathode ray tube 13 is so designed that its electron gun 14 is supplied with a low-frequency component of a luminance signal which is identified as Y_L. This low-frequency component Y_L is supplied by the amplifier 15 and has a value of for example 0 to 2 mc. The electron gun 14 is also supplied with a high frequency component Y_H of a luminance signal which varies from 2 to 4 mc. and the chrominance signal C_S, these components being supplied by the amplifier 16.

The chrominance C_S is fed to a color burst signal separator 17 to which is also applied one portion of the output from the horizontal deflection circuit 18. The horizontal deflection circuit 18 has applied thereto the horizontal synchronizing signal P_H which selects the color burst signal. The output of the color burst signal separator 17 is fed to a color switching signal generator 25 from which is obtained a sinusoidal signal f_s of 3.58 mc. The signal f_s is applied to the outer electrodes 19b and 20a of the cathode ray tube 13. In addition, one portion of the sinusoidal signal f_s is fed to a multiplier 21 from which is obtained a sinusoidal signal 2f_s of 7.16 mc. which is applied to the outer electrodes 19a and 20b. Further, one portion of the sinusoidal signal f_s of 3.58 mc. is fed to a key-out signal generator 22. A key-out signal of 10.7 mc. is obtained from the key-out signal generator 22 and is applied to the electron gun 14 after first being superimposed on the low-frequency component Y_L of the luminance signal Y which has been transmitted from the amplifier 15. In addition, the deflection yoke 24 is supplied with the outputs from the horizontal deflection circuit 18 and the vertical output circuit 23.

The color cathode ray tube 13 includes a color phos-

porous screen 26 which is composed of red, green and blue phosphorous strips which are identified respectively by the designations R, G and B. These phosphorous strips extend vertically across the face of the tube 26 and are sequentially arranged in a repeating cyclic order which, for example, may be red, green, blue, red, etc. Adjacent to the color phosphorous screen 26 and within the tube 13 there is provided a color selection grid 27 which is composed of many grid wires 27a. The grid wires 27a are positioned opposite the lines of demarcation between the green and blue phosphorous strips G and B and extend parallel to these phosphorous strips throughout their length. The electron beam 28 emanating from the electron gun 14 is caused to always impinge upon the red phosphor strips R and the color selection grid 27 is supplied with a potential which is lower than the potential applied to the color phosphor screen 26. In addition, the inner surface of the conical portion 13a of the tube 13 is coated with a high voltage conductive layer 29 to which a high potential is applied.

In accordance with the present invention two pairs of electrodes 19a, and 19b and 20a, 20b are mounted on the neck portion of the cathode ray tube 13. These electrodes as illustrated in FIG. 1 are mounted in front of and to the rear of the deflection yoke 14, i.e., at opposite ends of the deflection yoke 14. The electrodes of each pair are also disposed opposite in a direction perpendicular to the longitudinal direction of the phosphor strips R, G, B, etc. The electrodes may be disposed in close proximity to the deflection yoke 14 or they may partly underlie the deflection yoke 14. The electrodes are formed by vapor depositing a coating of, for example, a conductive material. It is preferred that the electrodes 20a and 20b which are located in front of the deflection yoke 14 partly extend over the conical portion 13a of the tube 13.

A layer of low resistance material is provided on the inner surface of the neck portion of the cathode ray tube 13 at those locations corresponding to the electrodes 19a, 19b and 20a, 20b. These low resistance layers are identified respectively as 46a, 46b, 47a and 47b. The area around these low resistance layers is coated with a high resistance layer 30 which has a resistance value which will be hereinafter described. One end of the high resistance layer 30 is grounded in AC current. It is preferred that the area of each low resistance layer 46a, 46b, 47a and 47b be of greater than the corresponding area of each of the electrodes 19a, 19b and 20a, 20b. In the embodiment illustrated in the drawings the high resistance layer 30 is formed around the low resistance layers 46a, 46b, 47a and 47b and on the inner surfaces of the conical portion 13a and on the neck portion 13b of the cathode ray tube 13 between the high voltage conductive layer 29 and the electron gun 14. In addition grooves 31 are formed in the high resistance layer 30, the grooves 31 extending parallel to the tube axis. The grooves 31 are utilized to apply a high voltage to the electron gun 14 from the high voltage conductive layer 29. For this purpose there is provided in each groove 31 a conductor 32 and the ends of the conductor 32 are joined to the high voltage conductive layer 29 and to the electron gun 14 respectively. One end of the high resistance layer 30 is grounded through the high voltage conductive layer 29 in the AC circuit. It is preferred that the conductors 32 be disposed at locations corresponding to the intermediate portions between the electrodes 19a and 19b.

As previously described, the color switching signals are applied to the outer electrodes 19a, 19b, 20a and 20b. For this purpose the output terminal of the color switching signal generator 25 is connected between the electrode 19b and ground, while the output of the multiplier 21 which produces the signal $2f_s$ is connected between the other outer electrode 19a and ground. In a similar manner the output side of the color switching generator 25 and of the multiplier 21 are connected respectively to the other pair of outer electrodes 20a and 20b, but the connections are in opposing relationship to the connec-

tions made to the electrodes 19a and 19b. In other words, the relationship is such that when the output side of the color switching generator 25 is connected to the electrode 19b it is also connected to the electrode 20a. In addition, a shield plate 34 is disposed on the outside of the outer electrodes 19a, 19b, 20a and 20b through an insulating layer.

In the color cathode ray tube described above, electrostatic capacitances 35a and 35b are established between the electrodes 19a and 19b as illustrated in FIG. 4. An electrostatic capacitance 36 is also formed between the adjacent layers 46a and 46b on the inside of the neck portion 13b of the cathode ray tube 13 since the layer 30 has a high resistance value. These capacitances 35a, 35b and 36 are equivalent to being connected together in a series as illustrated in FIG. 4. Moreover, since the end of the high resistance layer 30 is grounded in AC current, the connecting points between the capacitances 35a and 36 or between the capacitances 35b and 36 are grounded through leakage resistors 37a and 37b of the high resistance layers in AC current. The reference numerals 38a, 38b, 39a and 39b designate the capacitances formed between the electrodes 19a, 19b, 20a and 20b and the shield plate 34. The reference numerals 48a, 48b, 49a and 49b designate the capacitances formed between the low resistance electrodes 46a, 46b, 47a and 47b and the shield plate 34. This means that the color switching generator 25 is connected between one end 40b of the series capacitances and the ground, and that the multiplier 21 is connected between the other end 40a and the ground. In this case, the output sides of the circuits 25 and 21 and the capacitances 38b and 38a respectively are connected in parallel and are adapted to function in parallel resonance with respect to the signals f_s and $2f_s$ respectively.

The resistance value of the high resistance layer 30 is so selected that the time constant which is dependent upon the resistance value of the leakage resistances 37a and 37b and upon the capacitance value of the capacitances 35a or 35b is greater than the period of the color switching signal f_s . Since the distance between the electrodes of the capacitances 35a or 35b is shorter than that of the capacitance 36, and the dielectric constant between these electrodes is greater than that of the capacitor 36, the capacitance value of the capacitances 35a or 35b is remarkably greater than that of the capacitor 36. Accordingly, the signal f_s is applied between the terminals 40a and 40b, namely between the electrodes 19a and 19b, and almost all of its signal voltage is concentrated on the capacitor 36. That is, an electrostatic field of the signal f_s is produced in the neck portion 13b of the cathode ray tube 13 corresponding to the portion between the electrodes 19a and 19b. In a similar manner an electrostatic field of the signal $2f_s$ is provided in the tube 13. These electrostatic fields are so composed as to produce a color switching electrostatic field 41 as illustrated in FIG. 5, the field 41 varying with the lapse of time.

In a similar manner a color switching electrostatic field 42 is formed between the low resistance layers 47a and 47b in the cathode ray tube 13 by the signals applied to electrodes 20a and 20b. This electrostatic field 42 is in opposite phase to that established by the electrodes 19a and 19b. In FIG. 4 the reference numerals 43a and 43b indicate the capacitances established by the electrodes 20a and 20b and the low resistance layers 47a and 47b. The reference numeral 44 designates a capacitor produced between the low resistance layers 47a and 47b and the numeral 45 identifies the leakage resistance between these capacitors.

Since the electrostatic fields are produced in the cathode ray tube 13 in the manner described above and the electron beam 28 is not deflected by the outer electrodes 19a, 19b, 20a and 20b at the zero portion 41R of the color switching signal 31, the electron beam impinges upon the red phosphor strip R as previously described.

In a similar manner when the color switching signal approaches its negative peak value 41G the electrode 19b becomes negative, the electron beam 28 is diverged on the side of the electrode 19a and is then converged on the side of the electrode 20b, thereafter impinging upon the green phosphor strip G adjacent the red phosphor strip R. When the color switching signal 41 approaches its positive peak value 41B, the electron beam 28 is diverged and is then converged in directions opposite to those in the foregoing, with the result that it impinges upon the green phosphor strip G. In this manner the electron beam is electrostatically deflected by the color switching signals, and the color switching signal is synchronized with the chrominance signal fed to the electron gun 14 so that a color picture is reproduced on the color phosphor screen 16.

Where the capacitance values of the capacitors 35a and 35b are for example 100 pf., and the resistance value of the leak resistances 37a and 37b are 10 MΩ, their time constant is one millisecond. This time constant is sufficiently greater than the period of the color switching signal when color reproduction is achieved in a dot-sequential manner. Accordingly, this invention is applicable not only to dot-sequential color reproduction but is also applicable to line-sequential color reproduction at a frequency of 5.25 kc. lower than 3.58 mc. The resistance value of the high resistance layer 30 is so selected that the charges stored on the inner wall of the tube 13 by the secondary electrons produced in the tube may be evolved through the layer 30. Therefore, when a beam current from the electron gun is approximately 300μa., if secondary electrons in the order of 50μa., which is about 1/6 of the current, are emitted from the color selection grid 27, and some secondary electrons of approximately 20μa., which is about 1/2.5 of 50μa. reaches the high resistance layer 30, the secondary electrons flow to the ground through one of the leakage resistors 37a or 37b. The voltage drop in each leakage resistor 37a or 37b is such that when its resistance value is approximately 10 MΩ, the voltage drop is 10μa. times 10 MΩ, or 100 v. This is smaller than the peak value of about 1.5 kvpp. of the color switching signal 41, so that if the leakage resistances 37a and 37b have a value in the range of 1 to 10 MΩ, a color switching electrostatic field is established in the tube and the potential distribution in the tube is not disturbed. The high resistance layer 30 can be formed by vapor deposition of, for example, chromium oxide.

In the case where the peak value of the color switching signal is 1.5 kvpp., which can be obtained by selecting the deflection angle at the neck portion 13b to be about 1°28', and the capacitance values of the capacitances 35a and 35b are 50 pf., the reactive power from a color switching signal of 3.58 mc. that passes through the two capacitors 35a and 35b is approximately 315 w. Where the inductance of a coil connected to both ends of the series capacitors is about 40μh., and the coil is adapted to resonate with the color switching signals and its Q is about 120, the power of color switching signal is 2.5 w. In practice, the value of the capacitors 35a and 35b can be made smaller, and therefore the deflection power can also be decreased. However, since the value of capacitance 38a, 38b, 39a and 39b to the shield plate 34 are approximately 30 to 200 pf., the deflection power is selected in the range of 3 to 10 w. in practice.

In a chromatron tube 13 having a color grid 27 disposed opposite to the color phosphor screen 26, the capacitance of the grid is about 2000 pf., the color switching signal is about 400 vpp., the reactive power is approximately 2000 w. and the deflection is about 25 w. (in the case where Q is 80). These values are about four and ten times as great as those of the cathode ray tube of the present invention. In addition, it is considered that color switching is electromagnetically effected in the vicinity of the neck portion. In this case, the capacitance of the resonance circuit including the deflection is about

700μf., the color switching signal is about 700 vpp., the reactive power is 1000 w. and the deflection power is approximately 11 w. (in the case where Q equals 90). These values are about 3.5 and 4.5 times as great as those of the cathode ray tube of the present invention.

It can accordingly be seen from the foregoing that the present invention requires an extremely low power for color switching. In addition, the construction of the color switching device is very simple as can be seen from the drawings. Furthermore, the distance of the grid wires 27a from the color selection grid 27 corresponds to the width of three phosphor strips and this distance is greater than that in conventional chromatron tubes. This invention does not necessitate connection of every other grid wire 27a and insulation of adjacent ones, and therefore enables relatively simple manufacture of the cathode ray tube. Moreover, the number of the phosphor strips constituting the picture element between adjacent grid wires 27a is great so that a picture can be reproduced with high resolution.

In the present invention the color switching frequency can be as high as 3.58 mc., but the deflection power required is small as described above. This enables electron beam deflection to be accomplished through the use of relatively small power by a color switching signal such that the signal $2f_s$ of the multiplied frequency is superimposed on the signal f_s . The period that the electron beam stays on each phosphor is lengthened as illustrated in FIG. 5, and the period of the electron beam moving from one phosphor strip is shortened. Therefore, the use of such a color switching signal provides a color cathode ray tube which is free from color distortion and which is stable in operation. In addition, in the present example the signals f_s and $2f_s$ can be applied separately between either one of the electrodes 19a and 19b and ground, and the capacitors 38a and 38b between the electrodes 19a and 19b and shield plate 34 are each utilized as one element of the resonance circuit of the signal supply circuit. The shield plate 34 can be used as one element of the input circuit of the color switching circuit as well as serving to prevent the color switching signal from radiating to the outside. In such a case, it is considered practical to apply the signals f_s and $2f_s$ in series between either one of the electrodes and the ground. In the present case, even if either one of the capacitors 38a and 38b is employed as one input circuit of the signal, another capacitor element is required at the other input circuit. In the cathode ray tube of the present invention, however, such a capacitance element is not required.

In the prior art it is considered that in order to accomplish color switching electrostatically a color switching deflection plate is disposed in the cathode ray tube in the same manner as an electrostatic deflection plate is disposed in a usual electrostatic deflection type cathode ray tube. In this case, however, a deflection voltage supply lead must be led outside of the tube and the same high potential as that applied to the high voltage conductive layer 29 must be fed to the color switching deflection plate in order to insure that the potential of the electron beam path is not disturbed by the insertion of the color switching deflection plate. Therefore, attention must be paid to insulating the lead for deflection AC voltage application and for high voltage application. This makes it difficult to maintain the deflection yoke in position, and the insertion of the color switching deflection plate is impossible. In the cathode ray tube of the present invention, however, electrodes 19a, 19b and 20a and 20b are supplied with only the color switching signal and are grounded in DC current, so that the difficult insulation problem illustrated above is not required. In addition, with only the electrodes 19a, 19b, 20a and 20b provided on the outside of the tube, such an adverse influence is occasioned on the inner surface of the neck portion 13b that it is charged with secondary electrons to such an extent as to change the potential of the elec-

tron beam path, thereby deteriorating focusing of the electron beam. In order to avoid this, the high voltage conductive layer 29 is extended on the inner surface of neck portion 13b at places corresponding to the electrodes 19a, 19b, 20a and 20b. The high voltage conductive layer 29 is grounded in AC current so that no color switching field is produced.

In the cathode ray tube of the present invention the low resistance layers 46a, 46b, 47a and 47b are provided in the neck portion 13b at places opposite to the electrodes 19a, 19b, 20a and 20b, and the high resistance layer 30 is provided at the places around the low resistance layers 46a, 46b, 47a and 47b, and their resistance values are selected as described above. As a result of this, a color switching field can be established in the cathode ray tube without any difficulty and the inner surface of the tube has a DC potential. That is, there is no possibility that the potential of the electron beam path varies to deteriorate focusing of the electron beam. In addition with the conductors 32 formed in the grooves 31 in the high resistance layer 30, a high voltage can be applied with a low resistance from the high voltage conductive layer 29 through the conductors 32 to the electron gun 14.

In the foregoing, the signal $2f_s$ is superimposed on the signal f_s but color switching can be carried out by superimposing a signal $3f_s$ having a frequency which is three times as high as the signal f_s . In some cases color switching may be effected by the signal f_s only and in such event the signal f_s can be applied to the electrodes 19a and 19b in opposed phase relationship.

It will be apparent to those skilled in the art that although a preferred embodiment of the invention has been described and illustrated, that many modifications and variations may be made thereto without departing from the the scope of the novel concepts of this invention as set forth in the appended claims.

We claim:

1. A cathode ray tube for producing color-images wherein color switching is accomplished by low power electrostatic fields, said cathode ray tube comprising an elongated neck portion having mounted therein an electron beam gun, one end of said neck portion opening into an enlarged sealed chamber, the end of said chamber opposite said gun consisting of a color phosphor screen upon which said electron beam generated by said gun impinges, a post acceleration and focusing grid within said chamber and opposite said color phosphor screen, said screen being made up of alternating phosphor strips of three primary colors on one of which said electron beam is normally focused through said grid, first and second pairs of elec-

trodes mounted at spaced positions on the outer surface of said neck portion with the electrodes of each pair being mounted opposite each other, first and second switching means for applying alternating current deflection voltages to said first and second pairs of electrodes, respectively, whereby an electrostatic deflection field is established between each of said pairs of electrodes for selectively deflecting said electron beam from said phosphor strips of said one color to the phosphor strips of the other two primary colors, a layer of low resistance material coated on the inner surface of said neck portion at positions thereof corresponding to the locations of said first and second pairs of electrodes, and a layer of high resistance material coated on the inner surface of said neck portions contiguous to and encompassing said layers of low resistance material.

5 2. A cathode ray tube in accordance with claim 1 wherein the ends of said high resistance layer are grounded in AC current.

10 3. A cathode ray tube in accordance with claim 2 wherein a deflection yoke surrounds said neck portion, and said first and second pairs of electrodes being mounted on said neck portion at opposite ends of said yoke.

15 4. A cathode ray tube in accordance with claim 3 wherein said deflection voltages applied to said first and second pairs of electrodes are in opposed relationship to thereby change the incidence angle of said electron beam with respect to said post acceleration and focusing grid.

20 5. A cathode ray tube in accordance with claim 4 wherein said first and second pairs of electrodes are grounded in DC current.

25 6. A cathode ray tube in accordance with claim 5 wherein a shield plate is mounted on said neck portion to surround and shield said electrodes.
